(57) **CLAIM**

We claim the ornamental design for a variable reflectance mirror device, as shown and described.

DESCRIPTION

FIG. 1 is a front perspective view of a variable reflectance mirror device of the present invention;

FIG. 2 is a front elevational view of the variable reflectance mirror device of FIG. 1;

FIG. 3 is a rear elevational view of the variable reflectance mirror device of FIG. 1;

FIG. 4 is a first side elevational view of the variable reflectance mirror device of FIG. 1;

FIG. 5 is a second side elevational view of the variable reflectance mirror device of FIG. 1;

FIG. 6 is a top plan view of the variable reflectance mirror device of FIG. 1; and,

FIG. 7 is a bottom plan view of the variable reflectance mirror device of FIG. 1.
